UNITED STATES PATENT OFFICE.

FRANK WALTER HAYWARD, OF NORWICH, ENGLAND.

ADVERTISING DEVICE.

SPECIFICATION forming part of Letters Patent No. 623,664, dated April 25, 1899.

Application filed June 11, 1898. Serial No. 683,211. (No model.)

To all whom it may concern:

Be it known that I, FRANK WALTER HAYWARD, a subject of the Queen of Great Britain, residing at Norwich, in the county of Norfolk, England, have invented certain new and useful Improvements in Advertising Devices, of which the following is a full and complete specification, such as will enable those skilled in the art to which it appertains to make and use the same.

This invention relates to advertising devices; and the object thereof is to provide an improved device of this class which is simple in construction and operation and which is particularly adapted for use in groceries and other business houses, a further object being to provide an advertising device which is attractive to the eye and which is designed to command the attention of the observer; and with these and other objects in view the invention consists in the device hereinafter described and claimed.

The invention is fully disclosed in the following specification, of which the accompanying drawings form a part, in which the separate parts of my improvement are designated by the same letters of reference in each of the views, and in which—

Figure 1 is a front view of my improved advertising device; Fig 2, a back view with the casing removed, showing the operative mechanism thereof; and Fig. 3, a side view thereof looking in the direction of the arrow X.

In the practice of my invention I provide two similar trains of gear-wheels, the first of which are designated by the reference-letters A, A² and A³, and the second by the reference-letters B, B², and B³. The wheels of the first train are mounted on shafts a, a², and a³, and the shaft a is provided with a spring-drum C, and the shafts a² and a³ are each provided with a pinion a⁴, and the wheel A operates in connection with the pinion a⁴ on the shaft a², and the wheel A² operates in connection with the pinion a⁴ on the shaft a³, and above the wheel A³ is a shaft D, provided with a pinion d, which is operated by the wheel A³. The second train of wheels B, B², and B³ are mounted on corresponding shafts b, b², and b³, respectively, and the shafts b² and b³ are each provided with a pinion b⁴, and the wheel B operates in connection with the pinion on the

shaft b², while the wheel B² operates in connection with the pinion b⁴ on the shaft b³.

Above and a little to the left of the shaft b³ is a shaft G, provided with a pinion g, which is operated by the wheel B³, and said shaft G is also provided with an escapement-wheel g², and said wheels and shafts are all mounted in a suitable frame, consisting of sides E and E², and connected with the upper portion of the side E² of said frame is a short arm F, with which is pivotally connected an escapement f, which operates in connection with the escapement-wheel g² and with which is connected a downwardly-directed arm f², which is similar to the pendulum of an ordinary clock, the pendulum being removed. The shaft G is supported by an arm g³ and the outer side E² of the frame, said arm being secured to said side of the frame, and mounted in said frame to the left of and a little above the pivotal support of the escapement f is a shaft M, with an escapement formed by an upwardly-directed arm m and a downwardly-directed arm m², each of which is provided with a hook or projection m³, and this escapement or the arms m and m² operate in connection with pins O, secured to the wheel A³, and said shaft M is provided with an upwardly-directed arm or lever m⁴, which is provided with a yoke-shaped end m⁵, and the shaft G, with which the escapement-wheel g² is connected, is provided with a crank g⁴, which passes through said yoke-shaped portion of the arm or lever m⁴.

The advertising device is preferably provided with a base P, as shown in Fig. 1, above which is a casing P², which incloses all the parts of the apparatus shown in Figs. 2 and 3, and said casing is provided with a circular face or dial plate P³, through the center of which the shaft D projects, and said shaft D is provided with a pointer R. The circular face or dial plate P³ is also provided with an annular space S around the perimeter thereof, in which are placed for the purposes of this description the words "you," "groceries," "Yes," "buy," "worth," "if," "Is," "living," "here," "life," and "your." The sentence intended to be pointed out by the pointer R is written or placed upon a ring made of tin or other suitable substance. This ring is movable and reversible and is sus-

pended in any desired manner and hangs in the annular space S (shown in Fig. 1) and shows the subject-matter thereon as though it were displayed on the dial-plate P³, and by 5 means of the shaft G and the crank g⁴, which forms a part thereof, the arm or lever m⁴ is given an oscillating motion, which causes the arms m and m² to operate alternately in connection with the pins O on the wheel A³, and 10 this wheel is stopped each time that one of said arms comes in connection with one of said pins, and the pointer R on the shaft D is correspondingly operated, said pointer being given an intermittent motion.

15 In the construction here shown the wheel A³ is provided with eighty-four teeth and the pinion d of the shaft D is provided with twelve teeth, and said shaft D is provided with a vertically-movable brake J, which rests there- 20 on and is designed to prevent irregular motion of said shaft caused by the sudden stop of the wheel A³, occasioned by the arms m and m². This brake may be of any desired form or construction and may or may not be 25 employed; but I prefer to employ the same for the purposes above specified. By means of this gearing and the pins O on the wheel A³ the pointer R is given twelve stops to one revolution of the wheel A³, the number of said 30 pins being six; but it will be apparent that this construction and arrangement may be modified to suit the form of advertisement employed.

The pointer R may be so set that the first 35 movement thereof will end at the word "Is," the second at the word "life," the third at the word "worth," and the fourth at the word "living," these successive movements of said pointer resulting in successively pointing out 40 the words of the sentence "Is life worth living?" and the next movement of the pointer will end at the word "Yes," the next at the word "if," the next at the word "you," the next at the word "buy," the next at the word 45 "your," the next at the word "groceries," and the next at the word "here," thus successively pointing out the words of the sentence "Yes, if you buy your groceries here."

It will be understood that the pointer R 50 moves always in the same direction, stopping successively at the words required by the construction of the sentence to be pointed out. Thus for the above sentence eleven stops would be made, one over each of the re- 55 spective words, and a twelfth stop would also be made at the top of the dial. Before making the twelfth and final stop the pointer in the construction shown revolves two and a quarter times, the last word pointed out be- 60 ing "here," ninety degrees from the top of the dial.

Instead of forming the sentence intended to be pointed out by the pointer R in the circu- 65 lar space S of the dial-plate, as herein de- 65 scribed, I may employ an annular ring or plate, which is detachably and reversibly

mounted in said space, on which the words of said sentence will be placed, and said annular ring or plate may be composed of tin or any suitable substance and may be suspended 70 from a hook or any suitable support.

It will be apparent that this form of advertisement may be provided to suit any particular business, and it will thus be seen that I accomplish the object of my invention by 75 means of a device which is simple in construction and operation and perfectly adapted to accomplish the result for which it is intended.

Having fully described my invention, I claim as new and desire to secure by Letters 80 Patent—

1. The herein-described advertising device, comprising a casing having a face or dial plate, a shaft which passes therethrough, and is provided with a pointer, and two trains of 85 gears each of which is operated by a spring- drum, one of the wheels of one of said trains being geared in connection with the pointer- shaft, and being provided on one side with projecting pins arranged at intervals in a circle thereon, and one of the wheels of the other train being geared in connection with a shaft on which is mounted an escapement-wheel, an escapement which operates in connection with said wheel, and a pivotally-supported 90 escapement operating in connection with said pins, said last-named escapement being operated directly by the shaft on which said escapement-wheel is mounted, substantially as 95 shown and described.

100 2. The herein-described advertising device, comprising a casing provided with a face or dial plate, and a pointer-shaft passing therethrough, and provided with a pointer, said casing being also provided with two trains of 105 gears, one of the wheels of one train being geared in connection with the pointer-shaft, and being provided with projecting pins ar- 110 ranged in a circle thereon, and one of the wheels of the other train being geared in con- nection with an escapement-shaft, provided with an escapement-wheel, and devices oper- 115 ated directly by said escapement-wheel for controlling the movement of the wheel which is geared in connection with the pointer-shaft, substantially as shown and described.

120 3. An advertising device, comprising a cas- ing provided with a face or dial plate, a shaft projecting therethrough, and provided with a pointer, and two sets of spring-operated 120 gears mounted in said casing, one of the wheels of one of which is in operative connec- 125 tion with the pointer-shaft, an escapement- shaft geared in operative connection with the other set of gears, and means connected di- rectly with said escapement-shaft, for con- trolling the movement of the wheel which is in operative connection with the pointer-shaft, substantially as shown and described.

130 4. The combination of two sets of gears mounted in a casing or support, a shaft D, one of said sets of gears in operative connec-

tion with said shaft, an escapement-shaft geared in connection with the other set of gears, devices connected directly with said escapement-shaft for controlling the movement of said shaft D, and means for actuating said sets of gears, substantially as shown and described.

5 5. The combination of two sets of spring-operated gears mounted in a casing or support, one of the wheels of one of which is in operative connection with a shaft mounted adjacent thereto and provided with pins arranged in a circle on one side thereof, a crank-shaft geared in connection with the other set 10 of gears, an escapement mounted in operative connection with the pins in said wheels and provided with an arm engaging said crank-shaft, substantially as shown and described.

15 6. In a clockwork-actuated advertising device of the character described, a dial-plate, words or characters circularly arranged thereon and without proper legible sequence, a shaft passing through said dial-plate and 20 fitted with a pointer, and devices connected with said clockwork whereby said pointer is given a forward positive intermittent motion over predetermined varying arcs of said dial-plate to point respectively to said words or

characters in the proper legible sequence, substantially as shown and described.

7. In a device of the character described, a dial-plate bearing characters circularly thereon, a shaft passing through said dial-plate and fitted with a pointer and connected 35 with means whereby said pointer is given a forward intermittent motion over said dial-plate to point out said characters, said means comprising two sets of gears one of the wheels of one of which is geared in connection with 40 said shaft and bears on one side a series of lugs arranged in a circle, the other of which trains is geared in connection with an escapement-wheel having an escapement, and means connected with the shaft of said escapement-wheel and engaging the lugs on the wheel 45 geared in connection with the pointer-shaft for controlling said wheel, substantially as shown and described.

In testimony that I claim the foregoing as 50 my invention I have signed my name, in presence of the subscribing witnesses, this 26th day of May, 1898.

FRANK WALTER HAYWARD.
